UNITED STATES PATENT OFFICE.

HARRY T. LAUGHTER, OF FLOYDADA, TEXAS.

WASHBOARD.

Application filed April 30, 1923. Serial No. 635,499.

To all whom it may concern:

Be it known that I, HARRY T. LAUGHTER, a citizen of the United States, residing at Floydada, in the county of Floyd and State of Texas, have invented certain new and useful Improvements in Washboards, of which the following is a specification.

This invention relates to an improved washboard construction.

10 An object is to simplify and improve the existing art by constructing a washboard comprising a metal body and wooden sides and connecting means therefor adapted to force the sides toward each other to cause 15 the edges of the body to enter said sides, and thereby associate the parts in any easy, expeditious, strong and efficient manner.

Another object is to produce a washboard 20 whose body is constructed of a single sheet of metal having its edges sharpened and thereafter bent or otherwise shaped to produce spaced rubbing surfaces, and a soap holding plate having a substantially semi-elliptical head, and wherein wooden sides 25 are employed and means for connecting the sides and body adapted to draw these elements toward each other to cause the sharpened edges of the body to enter the sides, and thus effectively associate these parts.

30 A still further object is to produce a washboard comprising a metal body whose edges are sharpened and which defines spaced ribbed or corrugated rubbing surfaces, a plate extending centrally from one 35 end thereof and which terminates in a semi-elliptical head, and wooden sides for the body, means of a particular and peculiar construction being disposed between the rubbing surfaces to properly space and reinforce the same, while means is passed through

40 the sides, the head and between the rubbing surfaces of the body for forcing the sides toward each other to cause the sharpened edges of the body to enter said sides, said 45 means also holding the reinforcing and spacing means in proper relation with respect to each other and with respect to the rubbing surfaces of the body.

To the attainment of the foregoing and 50 other objects which will present themselves as the nature of the invention is better understood, the invention consists in the improvement as hereinafter described and definitely claimed.

In the drawings which accompany and 55 form part of this application:—

Figure 1 is a front elevation of a washboard in accordance with my improvement, parts being broken away and parts being 60 in section.

Figure 2 is a sectional view on the line 2—2 of Figure 1.

Figure 3 is a sectional view on the line 3—3 of Figure 1.

Figure 4 is a fragmentary perspective view 65 of one of the reinforcing and spacing elements for the rubbing surfaces of the body of the washboard.

Figure 5 is an enlarged fragmentary transverse sectional view better illustrating the 70 manner in which the sharpened edges of the metal body are arranged in one of the wooden sides.

Figure 6 is a fragmentary transverse sectional view through one of the rubbing surfaces of the body.

The body of my improvement is formed from a sheet of metal, and the sides are of wood. The metal sheet, before being shaped to constitute the parts hereinafter to be described, has its edges sharpened and the wooden sides are water soaked so that the sharpened edges of the body will enter the 80 said sides when the connecting means between the body and sides are adjusted.

The sides 1 are of the usual construction in which the grain of the wood runs longitudinally.

The metal body has one of its ends shaped to provide a substantially semi-elliptical top 90 or head portion 2. From the under flat face there is centrally extended the plates 3 that constitutes the side wall of the soap holder. The plate 3 may be formed with serrations 95 at its sharpened edges, and the said plate is bent at an outward angle to provide a ledge 4 on which a bar of soap is designed to rest. The plate 3, above the shoulder 4 is provided with spaced transverse openings 100 5 whereby saponaceous fluid can flow from one to the other face of the said plate. From the ledge or shoulder 3 the plate is extended to provide a ribbed or corrugated rubbing surface 6. The surface 6 has its lower end bent at an inward angle, as at 7, and from thence at an opposite or outward angle, as at 8. From the angle portion the plate constituting the body is continued to provide 105

a second rubbing surface 9 which is, of course, arranged parallel with the rubbing surface 6. The corrugations on the surface 9 are spaced a greater distance apart than those on the surface 6, and the upper end of the said surface 9 is bent inwardly, as at 10, toward the ledge or shoulder 4. The ledge 10 preferably underlies the ledge 4 and is soldered or otherwise suitably connected thereto. The confronting surfaces of the head 2 may be likewise connected.

The water soaked sides 1 are provided with spaced aligned openings, the upper openings being arranged to align with the hollow head 2 of the body and to receive a bolt 11 therethrough. This greatly facilitates in properly arranging the metal body centrally between the sides and thereafter other bolts 12 are passed through the remaining openings in the sides and are also passed between the rubbing surfaces 6 and 9 of the body. It is to be understood that aside from these openings, the sides 1 are not channeled or grooved for the reception of the edges of the metal body of the wash board. All of the bolts are engaged by nuts 13 respectively, but before the nuts are applied there is arranged between the rubbing surfaces 6 and 9 of the body spacing and reinforcing means of a particular and peculiar construction. This means comprises flat wooden blocks 14 which have forced into the ends thereof corrugated portions 15 provided on flat metal strips 16. The wooden members 14 are in contacting engagement with the confronting faces of the surfaces 6 and 9. By reference to the drawings it will be seen that three bolts 12 are employed, and that I make use of two of the spacing and reinforcing elements. One of these elements is arranged between the lower and intermediate bolt 12, the other being arranged between the intermediate and upper bolt, and by this arrangement it will be noted that the said spacing and reinforcing elements are effectively supported. The nuts 13 are now screwed home on the bolts and bind against washers 17 to cause the latter to contact with one of the sides to draw both of the sides 1 toward each other and thus force the sharpened edges of the body into the sides 1. In this manner it will be noted that the body is easily, quickly, and effectively secured in the sides and held from movement in any direction therefrom.

In my washboard construction a solid filler to provide a reinforcement between the rubbing surfaces is not desirable, as the same must be cut to a nicety, it being understood that the reinforcement does not enter the wooden sides but firmly contacts therewith

when the parts are associated. With my reinforcing construction, the outer wooden members may contact the sides of the board and guide the metal body when its sharpened edges enter the board upon the screwing home of the nuts on the bolts. The movement of the sides of the washboard toward each other will exert a pressure against the outer wooden members of the reinforcing means, which pressure will be resisted by the metal straps which connect all of the wooden members of the said reinforcing means, and such resistance may cause a slight springing or bulging of the said metal straps. By arranging the reinforcing means between the end and central bolts 12, the bolts are properly guided when passed through the sides and through the metal body of the wash board.

It is thought from the foregoing description, that the advantages and novel features of my invention will be readily apparent, but it is to be understood that I am not to be confined to the precise structural details herein set forth, and may make such changes therefrom as fall within the scope of my claims without departing from the spirit of the invention.

Having described the invention, I claim:

1. In a washboard construction, plain wooden side members, a metal rubbing surface having sharpened edges interposed between the sides, and adjustable means passing through the sides and the metal rubbing surface for forcing the sides under pressure toward each other to cause the sharpened edges of the rubbing surface to enter said sides, whereby said edges are embedded in and secured against outward movement on the sides.

2. In a washboard construction, plain soft wooden side members, a hollow metal body providing spaced rubbing surfaces interposed between the sides, and said body having its edges sharpened, adjustable means passing through the sides and through the metal body for forcing the sides under pressure toward each other to cause the sharpened edges of the body to enter said sides so that the edges will be embedded in and secured against movement on the sides, and combined spacing and reinforcing means in the body and resting on and held from vertical movement by the adjustable means passing through the body, said spacing and reinforcing means comprising wooden blocks and spaced metal strips connecting the blocks.

In testimony whereof I affix my signature.
HARRY T. LAUGHTER.
